BRINE CABINET INNER BOTTOM

Robert E. Marsh, Milwaukee, Wis.
(5521 Willow View Road, Racine, Wis. 53402)

Filed Feb. 8, 1971, Ser. No. 113,809

Term of patent 14 years

Int. Cl. D23—01

U.S. Cl. D23—3

FIG. 1.

FIG. 2.

FIG. 3.

FIG. 4.

FIG. 5.

FIG. 1 is a top perspective view of the cabinet inner bottom embodying my new design;

FIG. 2 is a side elevational view thereof;

FIG. 3 is an end elevational view thereof;

FIG. 4 is a top plan view thereof; and

FIG. 5 is a bottom plan view thereof.

I claim:

The ornamental design for a brine cabinet inner bottom, as shown.
